UNITED STATES PATENT OFFICE.

CHARLES J. GUSTAFSON, OF READING, PENNSYLVANIA, ASSIGNOR, BY MESNE ASSIGNMENTS,
TO READING STANDARD COMPANY, A CORPORATION OF PENNSYLVANIA.

MUFFLER.

No. 888,489.

Specification of Letters Patent.

Patented May 26, 1908.

Application filed November 1, 1906. Serial No. 341,533.

To all whom it may concern:

Be it known that I, CHARLES J. GUSTAFSON, a subject of the King of Sweden, and a resident of the city of Reading, county of Berks, and State of Pennsylvania, have invented certain new and useful Improvements in Mufflers, of which the following is a specification.

My invention relates particularly to mufflers for internal combustion engines and my main objects are to thoroughly eliminate the objectionable noise ordinarily produced by the exhausting gases of combustion while securing proper freedom of the exhaust; and at the same time to provide a device of simple and substantial construction.

The invention is fully described in connection with the accompanying drawing and the novel features are specifically pointed out in the claims.

Figure 1 is a longitudinal sectional view of a simple form of muffler embodying the features of my invention. Fig. 2 is an end view of the same.

In my improved muffler, as shown, the exhaust is discharged through a central tube *a*, extending the full length of the muffler and open throughout its length; there being grouped around the main portion of this tube a series of concentric cylinders *b*, *c* and *d*, united by cylinder heads *h* and *m* near the opposite ends of the tube and forming a corresponding series of annular chambers *e*, *f* and *g*; the outer one of which chambers communicates directly with an annular exhaust-inlet chamber *n* formed in the head *m* around one extremity of the tube, and indirectly with the latter, so that the exhaust gases are passed through each of the concentric chambers and finally discharged through the central open tube, as hereafter described.

In the preferred construction indicated, the concentric cylinders *b*, *c* and *d* surrounding the central tube *a*, are carried by opposite heads *h* and *m* suitably fixed to the latter. Said head *h* forms a closure at one end for all of the annular chambers *e*, *f* and *g*, while the opposite head *m*, as shown, is formed with an exhaust inlet chamber *n* surrounding the end portion of the tube *a* and having an exhaust pipe connection *p*. This chambered head *m* is provided with an inner circular flange *q* fitting upon the end of the outer concentric cylinder *d*, and with a partition plate *r* upon which the ends of the

smaller cylinders *b* and *c* are properly spaced and supported; the exhaust inlet chamber *n* being left in free communication with the outer annular chamber *g* around the main portion of the tube *a*.

The passage of the exhaust gases through the successively reduced chambers *g*, *f* and *e*, into the central discharge tube *a*, is circuitous, as indicated by the arrows; the communicating openings *s*, *t* and *u* being located alternately near opposite ends. Thus the gases entering the larger outer chamber *g* through the inlet chamber *n* are at once freely expanded, thereby greatly reducing their velocity and temperature; after which their further movement to the final point of discharge through the central tube *a* is restricted as indicated so as to apparently cushion the successive exhaust blasts within the muffler and thereby effectively eliminate the noise without involving back pressure in the cylinder. This desired result is very satisfactorily attained in practice; thus providing a very effective muffler as to operation, while at the same time the construction is most simple and strong. The central discharge tube *a* may be left open at both ends, or be closed at one end, and the specific construction shown otherwise modified.

What I claim is:

1. A muffler comprising a central discharge tube, concentric cylinders forming communicating annular chambers around the main portion of said tube, a closed cylinder head upon one end of said central tube, a cylinder head upon the opposite end of said tube and being formed with an annular exhaust inlet chamber open on one side only and communicating with the outer annular chamber, and a ring arranged upon said tube adjacent the second cylinder head for closing the ends of the inner chambers.

2. A muffler comprising a central tube, an inlet cylinder head on one end and being formed with an annular groove open on the inner side of the inlet head and forming an exhaust inlet chamber, concentric cylinders forming communicating annular chambers around the main portion of the tube, a closed cylinder head on the opposite end of the tube closing that end of the cylinders, and a ring arranged upon said tube and closing the inner circumferential portion of the opening in the side of the inlet cylinder head and also closing the adjacent ends of the inner or

central cylinders, said annular exhaust inlet chamber communicating through the outer circumferential portion of the said opening with the outer annular chamber.

- 5 3. In a muffler, a central discharge tube, concentric cylinders forming communicating annular chambers around the main portion of the tube, cylinder heads embracing the ends of the outer cylinder, a ring upon the 10 tube, said ring and one of said cylinder heads embracing the ends of the remaining cylinders, one of said heads being formed with an inlet opening and an annular exhaust inner

chamber open on the inner side only of the head, said open side being partially covered 15 by said ring and the outer annular chamber being in communication with the annular exhaust inlet chamber through the remaining uncovered portion of said open side.

In testimony whereof, I affix my signature, 20 in the presence of two witnesses.

CHARLES J. GUSTAFSON.
